Primary Examiner — Catherine Ho(74) *Attorney, Agent, or Firm* — Birch, Stewart, Kolasch & Birch, LLP(57) **CLAIM**

We claim the ornamental design for a combined digital signage and pole, as shown and described.

DESCRIPTION

FIG. 1 is a perspective view of a combined digital signage and pole showing our new design;
 FIG. 2 is a front elevation view thereof;
 FIG. 3 is a rear elevation view thereof;
 FIG. 4 is a left-side elevation view thereof;
 FIG. 5 is a right-side elevation view thereof;
 FIG. 6 is a top plan view thereof;
 FIG. 7 is a bottom plan view thereof; and,
 FIG. 8 is a perspective view shown in an environment of use. The broken line showing in FIGS. 1, 6 and 7 is for the purpose of illustrating portions of the combined digital signage and pole and forms no part of the claimed design. The broken line showing in FIG. 8 is for the purpose of illustrating environment and forms no part of the claimed design.
